Primary Examiner — Natasha Vujcic*Assistant Examiner* — Gilbert B Ford(74) *Attorney, Agent, or Firm* — Polsinelli PC**CLAIM**

The ornamental design for a spikeable evacuation bottle as shown and described.

DESCRIPTION

FIG. 1 is a front, top, right side perspective view of a spikeable evacuation bottle showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear, bottom, left side perspective view thereof. The broken lines depict portions of the spikeable evacuation bottle that form no part of the claimed design.
